UNITED STATES PATENT OFFICE.

CHARLES T. SLEEPER, OF CHICAGO, ILLINOIS, ASSIGNOR OF ONE-HALF TO
GEORGE PLUMER EVERHART, OF SAME PLACE.

SALES-RECORDER.

SPECIFICATION forming part of Letters Patent No. 576,079, dated January 26, 1897.

Application filed October 9, 1895. Serial No. 565,142. (No model.)

To all whom it may concern:

Be it known that I, CHARLES T. SLEEPER, a citizen of the United States, residing at Chicago, in the county of Cook and State of Illinois, have invented certain new and useful Improvement in Sales-Recorders, of which the following is a specification.

My invention relates to sales-recorders, and has for its object to produce a new and improved device to be used in stores or like places which will record the sales as they are made.

My invention is illustrated in the accompanying drawings, wherein—

Figure 1 shows a plan view of a device embodying my invention. Fig. 2 shows a side view with one side of the case or cover removed, so as to expose the working parts. Fig. 3 is a longitudinal section on line 3 3, Fig. 1. Fig. 4 is a cross-section on line 4 4, Fig. 1. Fig. 5 is an enlarged side view of one of the type-carrying bars. Fig. 6 is a plan view of the same. Fig. 7 is a detail of the spacing mechanism. Fig. 8 is a view showing the openings through which the amount of the sale to be recorded is seen. Fig. 9 is a view of a portion of the paper upon which the sales are recorded.

Like letters refer to like parts throughout the several figures.

The mechanism of my device is contained within the case A, which is hinged at A', so that it may be moved away from the mechanism in order to examine and adjust the parts and to remove and replace the material upon which the record is made. Hinged at one side of the case is a lever B. A similar lever B' (see Fig. 3) is hinged on the other side of the case, the two levers being joined together by the cross-piece B². Attached to this cross-piece is the arm B³, which projects through the case and by which the device is operated. Said levers B and B' are forced upwardly by the springs B⁵ B⁶. Each of said levers is provided with a projecting lug B⁶, adapted to come in contact with the short rod B⁷ near the limit of the downward movement of said levers. The said rod B⁷ is connected with the lever B⁸, pivoted at B⁹. Said lever is normally so positioned that its end engages the end of the

cash-drawer B¹⁰ and prevents it from being opened. When the rod B⁷ is engaged by the lugs on the levers B and B', the end of the lever B⁸ is lifted so as to release the cash-drawer. Said cash-drawer is then forced open by the coil-spring B¹¹.

Associated with each of the levers B and B' are the bars C C'. These bars are provided with enlarged ends, having the diagonal slots C² C². The lower end of each of these slots is vertical, as shown at C³. Attached to the levers B and B' are the pins B⁴, adapted to engage or enter into the slots in the ends of the bars C C'. Said slots C² are virtually cam-slots and, in connection with the pins B⁴, form a cam arrangement, by which said levers are reciprocated. Said bars are connected to the frame D, upon which the mechanism of the recorder is supported, the connection being such that said bars are adapted to have a reciprocating motion. The rear end of the bar C engages with the teeth on the ratchet-wheel E, and hence when said bar is reciprocated the ratchet-wheel will be rotated. Said bar is provided with an opening C⁴, in which works the roller C⁵. Said opening is made larger than the roller, so that the bar may have a vertical motion, in order that it may spring down, so as to pass the teeth on the ratchet-wheel as it is drawn backward. Said bar is held in position to engage the ratchet-wheel by the spring C⁶.

Journaled to the frames D are the three rollers D' D² D³, which carry the paper upon which the registrations are made. This paper, before the registrations are made upon it, is rolled upon the roller D'. One end of the paper is then passed over the roller D² and is connected with roller D³, the paper being wound upon said latter roller after the registrations are made upon it. The ratchet-wheel E is rigidly connected with the roller D³. The registrations are made upon the paper as it passes over the roller D², said roller being preferably covered with rubber or the like material. The roller D³ is provided on its surface with a roll of projecting pins or points D⁵. These points are so constructed and arranged as to puncture the paper as it is wound upon the roller D³, so that it may be separated into 100

pieces equal in length to the circumference of said roller. Said roller is provided at one end with a wheel D^6 . (See Fig. 7.) This wheel is provided with a single notch D^7 . The wheel D^6 is made substantially one-half the diameter of the ratchet-wheel E , and the end of the bar C' is bent upwardly, so as to engage said wheel. The motion of the bar C' has no effect upon the wheel D^6 until such wheel reaches a position where said bar will engage the notch D^7 . The movement of the bar when in this position, due to the downward movement of the levers B and B' , rotates the roller D^3 , and since the wheel D^6 is one-half the size of the wheel E said roller will be moved through a distance equal to two teeth on said wheel E . By this construction an extra or enlarged space is made between the registrations at each revolution of the roller D^3 , as is shown at D^8 in Fig. 9. The pins or points D^5 are so positioned that the perforated line on the paper is made at D^9 , thus leaving the space D^8 at the bottom of each piece for the sum of the items thereon. By this arrangement the paper, after it has been taken from the machine, may be separated at the places where it is perforated and the different parts may be bound into a book, which will show the record of sales as they have been made and which will have a space at the bottom of each sheet for the sum of the items recorded upon such sheet. The figures by which the impressions are made upon the paper are attached to the lower side of the movable or sliding bars F . An inked tape E' passes over the roller D^2 between the bars F and the paper on said roller. This tape is wound upon the roller E^3 , Fig. 4, and after passing across the face of the roller D^2 is wound upon the roller E^3 . A short shaft E^4 (see Fig. 2) is connected with the roller E^3 , and is provided at its end with a friction-wheel E^5 , adapted to engage a friction-ring E^6 on the face of the ratchet-wheel E . The shaft E^4 is free to move longitudinally, and is pressed against the friction-ring E^6 by the spring E^7 . By this construction the inked tape is moved each time the levers B and B' are moved downwardly, so as to present a new surface to the figures on the bars F . The ratchet-wheel E is prevented from moving backward by the pawl E^8 .

The figures or type upon the bars F may be arranged in any manner desired, but I prefer to have them run from "0" to "9" consecutively. The upper side of each of the bars F is provided with the rack F' , each rack engaging a pinion F^2 on the shaft F^3 . These pinions engage similar pinions F^4 upon the shaft F^5 . Said shaft also carries the disks F^6 , which are numbered upon the periphery in the same manner as the bars F . The case A is provided with the openings A^3 A^3 , through which the numbers on said disk are exposed. The bars F are connected with the frame F^8 , which is pivoted at F^8 . This frame is normally held from engagement with the paper

on the roller D^3 by means of the spring F^9 . As shown in the drawings, the bars F are slotted, the end F^{10} of the frame working in said slots, as shown in Figs. 3 and 5. By this construction the bars can be reciprocated or moved back and forth, so as to bring any desired figure over the ribbon E' . Connected to the lower end of each of these bars is the thumb-piece G , by which they are controlled. Pivoted at the lower end of each bar F is a lever G^2 , (see Fig. 5,) provided at its end with a roller G^3 and pressed downwardly by means of a spring G^4 . At each side of said bars when they are in position are the corrugated strips or racks G^5 G^5 , (see Fig. 1,) said racks being so positioned that they are engaged by the rollers G^3 . As the bars are moved backward and forward these rollers pass along the racks G^5 , the spring G^4 allowing them to move past the teeth on the rack and pressing them down between the teeth, so that they can be held in any desired position.

The top of the case A is numbered, as shown in Fig. 1, so that when the thumb-piece G of any bar is opposite a given number said number will be over the ribbon E' , so as to be in position to be recorded on the paper, and the disks F^6 are so numbered and so connected with said bars that the same number will be exposed through the openings A^3 of the case. The frame F^7 is connected with each of the levers B and B' by means of the bars H H . Said bars are pivotally connected to said levers, and are connected to the frame F^7 by means of the pins H' . The upper ends of said bars are provided with the slots H^2 , so that they may be moved without moving the frame F^7 . These slots are of such length that said frame will only be moved when the levers B and B' are near the downward limit of their movement. Each of the bars F is provided with slots or recesses H^3 , (see Fig. 5,) adapted to be engaged by the dogs H^4 on the shaft H^5 . Said slots are so positioned as to be engaged by said dogs only when the bars are drawn completely back, so that there is no number over the tape E' . Rigidly connected with the shaft H^5 are the arms H^6 , provided at their ends with hooks adapted to engage the pins H^7 on the bars H . When said hooks are in engagement with the pins, the levers B and B' cannot be moved downwardly far enough to move the lever, which prevents the cash-drawer from opening. When the bars F are moved forward, the dogs will be moved out of the slots H^3 and the arms H^6 will be tilted backward, so as to be disengaged from the pins H^7 , and thus allow the levers B and B' to be moved to their extreme downward limit.

I have described these several parts in detail, but it is evident that they may be greatly varied in form, construction, and arrangement and that some of the parts may be omitted and others used in connection with parts not herein shown without departing from the

spirit of my invention, and I therefore do not wish to be limited to the construction herein shown and described.

The use and operation of my invention are 5 as follows:

When it is desired to record a given sale, the bars F are moved so as to bring the thumb-pieces G opposite the numbers which represent the sale, the cents being designated by 10 the two columns at the right, Fig. 1, and the dollars by the two columns at the left. When in this position, the same figures will show through the openings A³. If now the arm B³ is pressed downwardly, the bars C will be 15 moved in the direction of the arrow by means of the pin B⁴ and slot C². The end of said bar engaging with the teeth on the ratchet-wheel E causes said ratchet-wheel to rotate and move the paper forward, thus moving 20 the previously-recorded sale from beneath the ribbon E'. As the bar continues to move downwardly the lugs B⁶, coming in contact with the rod B⁷, move the lever B⁶ so as to release the cash-drawer B¹⁰, and said drawer 25 is forced open by its spring. Just before the levers B and B' reach the downward limit of their motion the ends of the bars H come in contact with the pins H' and the arm F' is moved downwardly, so as to cause the characters 30 opposite the tape E' to forcibly strike said tape, so as to be impressed upon the paper beneath. When the characters on the bars F strike the inked tape E', the pin B⁴ is moving in the straight part C³ in the slot in 35 the end of the bar C, and hence the paper at this time will be stationary, as the bar C will not be moved during this part of the motion of the pin. The arm B³ is now released and the springs B⁵ move the levers B and B' back 40 to their normal position, the spring F⁹ also moving the frame F' back to its normal position. The tape is moved, as described before, by the contact between the friction-wheel E⁵ and the ring E⁶. I prefer to have 45 the bars F so situated with relation to the roller D² that they will only need to be moved a very short distance in order to make contact therewith. I may of course use as many 50 of the bars F as desired, although I have only shown four in the drawings. When it is desired to construct the machine so that the money-drawer may be opened for any reason, such as making change, I may place, instead 55 of the "0" on the bar F to the right, Fig. 1, the words "No sale." If now the thumb-piece G is moved opposite the words "No sale" on the case, the dogs H⁴ will be removed from the slots in the bars F and the arm H⁶ will be moved out of engagement with the pins H⁷. 60 If the lever B³ is now moved downwardly, the words "No sale" will be recorded upon the paper and the money-drawer will be opened. I may also provide the recorder with an additional bar F, having thereon the names of different articles to be sold, so that in addition 65 to the registration of the sale there will also be recorded the article sold.

It will be seen that I have here a simple cash and sale recorder that can be constructed at a small cost and which will accomplish 70 satisfactorily all of the things necessary to make a complete record of the articles sold.

I claim—

1. A sales-recorder comprising a series of substantially rigid reciprocating bars, each 75 carrying a number of the characters by which the registrations are made, a surface with which said characters are adapted to make contact, said surface so constructed and arranged that each character may be separately 80 brought into contact therewith, a movable operating arm or lever connected with said bars so as to move them toward said contact-surface, and a connection between said lever and said contact-surface whereby said surface is moved each time the recorder is operated, so as to present a new surface to the characters on the reciprocating bars.

2. A sales-recorder comprising one or more rollers carrying the paper upon which the registrations are made, a reciprocating bar associated with one of said rollers so as to engage it when reciprocated and move the paper forward by a step-by-step feed, a second reciprocating bar associated with one of said 90 rollers and adapted to engage it once during each revolution, an operating arm or lever connected with both of said bars so as to reciprocate them when the arm is moved, and a supporting device carrying a series of numbers or characters adapted to be moved by the movement of said operating-arm so as to make contact with the paper on said roller or 95 rollers.

3. A sales-recorder comprising a series of 105 rollers carrying the paper upon which the registrations are made, a reciprocating bar associated with one of said rollers so as to engage it each time the bar is reciprocated and move the paper forward by a step-by-step 110 feed, and a pivoted arm or lever engaging said bar so as to reciprocate it when said arm is moved, a supporting device carrying a series of numbers or characters adapted to be moved by the movement of said operating-arm, so as 115 to make contact either singly or combined with the paper on said roller, and an inked tape passing between said numbers or characters and the said paper and connected with one of said rollers so as to be moved along 120 the surface of the paper when the rollers are moved, whereby the desired numbers or characters are printed upon the paper when the operating-lever is moved.

4. A sales-recorder comprising a series of 125 rollers carrying the paper upon which the registrations are made, a series of figures or characters adapted to be brought into contact with said paper, a supporting device for said characters, a reciprocating bar associated 130 with one of said rollers so as to engage it when reciprocated and move the paper forward by a step-by-step feed, whereby a space is made between the successive registrations on the

paper, a second reciprocating bar associated with one of said rollers and adapted to engage it at one point in its revolution so as to move the paper forward a greater distance than when moved by said first-mentioned bar, and provide an enlarged space between the registrations at every revolution of said roller, an operating arm or lever connected with said bars so as to reciprocate them when said arm is moved, a series of projecting pins or points extending across the surface of one of said rollers, said pins so positioned as to perforate the paper at the end of each enlarged space thereon whereby the paper may be separated into strips provided at the end with a blank space substantially as described.

5. A sales-recorder comprising a series of rollers carrying the paper upon which the registrations are made, a series of reciprocating bars opposed to one of said rollers and carrying the figures or characters to be recorded, a pivoted frame to which said bars are connected so as to be moved thereby, a reciprocating bar associated with one of said rollers so as to engage it when reciprocated and move the paper forward by a step-by-step feed, whereby a space is made between the successive registrations on the paper, a second reciprocating bar associated with one of said rollers and adapted to engage it at one point in its revolution so as to move the paper forward a greater distance than when moved by said first-mentioned bar, and provide an enlarged space between the registrations at every revolution of said roller, an operating arm or lever operatively connected with the said frame, said operating-lever connected with said last-mentioned bars so as to reciprocate them when said arm is moved, a series 40 of projecting pins or points extending across the surface of one of said rollers, said pins so positioned as to perforate the paper at the end of each enlarged space thereon, whereby the paper may be separated into strips provided at the end with a blank space substantially as described.

6. A sales-recorder comprising a series of rollers carrying the paper upon which the registrations are made, a series of reciprocating bars opposed to one of said rollers and carrying the figures or characters to be recorded, a pivoted frame to which said bars are connected, said frame being connected to the operating arm or lever so as to be moved thereby, a connection between said bars and a series of disks carrying characters similar to those on said bars adapted to be exposed through openings in the case, and a connection between said operating-arm and said rollers 60 whereby the paper is moved forward each time said operating-lever is moved.

7. A sales-recorder comprising one or more rollers carrying the paper upon which the registrations are made, a reciprocating bar associated with one of said rollers so as to move it when reciprocated and move the paper forward by a step-by-step feed, a slot in the end

of said bar and an operating arm or lever provided with a pin adapted to work in said slot whereby said bar is reciprocated when said operating-lever is moved, said slot consisting of two portions, one at an angle with the direction of movement of said operating-arm, the other portion being parallel with said movement so that the bar is not moved during the latter part of the movement of said operating-arm.

8. A sales-recorder comprising a series of rollers carrying the paper upon which the registrations are made, a series of reciprocating bars opposed to one of said rollers and carrying the figures or characters to be recorded, a reciprocating bar associated with one of said rollers so as to move said roller when reciprocated and move the paper forward by a step-by-step feed, a slot in the end of said reciprocating bar, an operating arm or lever provided with a pin adapted to work in said slot so as to reciprocate the bar when the operating-lever is moved, said slot so constructed that the bar is not moved by the movement of said operating-arm when near the downward limit of its movement, and a connection between said operating-lever and the reciprocating bars carrying the characters, said connection so constructed that said latter reciprocating bars are moved only when the operating-arm is near the limit of its downward movement.

9. A sales-recorder comprising a series of rollers carrying the paper upon which the registrations are made, a series of reciprocating bars opposed to one of said rollers and carrying the figures or characters to be recorded, a reciprocating bar associated with one of said rollers so as to move said roller when reciprocated and move the paper forward by a step-by-step feed, a slot in the end of said reciprocating bar, an operating arm or lever provided with a pin adapted to work in said slot so as to reciprocate the bar when the operating-lever is moved, said slot so constructed that the bar is not moved by the movement of said operating-arm when near the downward limit of its movement, and a connection between said operating-lever and the reciprocating bars carrying the characters, said connection so constructed that said latter reciprocating bars are moved only when the operating-arm is near the limit of its downward movement, a locking device for the money-drawer adapted to be engaged by said operating-lever, so as to be moved to release said drawer, and a locking device for said operating-lever which prevents it from being moved so as to unlock said money-drawer until the recorder is set to record a sale.

10. A sales-recorder comprising a series of rollers carrying the paper upon which the registrations are made, a series of reciprocating bars opposed to one of said rollers and carrying the figures or characters to be recorded, a reciprocating bar associated with one of said rollers so as to move said roller when

- reciprocated, and move the paper forward by a step-by-step feed, a slot in the end of said reciprocating bar, an operating arm or lever provided with a pin adapted to work in said slot so as to reciprocate the bar when the operating-lever is moved, said slot so constructed that the bar is not moved by the movement of said operating-arm when near the downward limit of its movement, and a connection between said operating-lever and the reciprocating bars carrying the characters, said connection so constructed that said latter reciprocating bars are moved only when the operating-arm is near the limit of its downward movement, a locking device for the money-drawer adapted to be engaged by said operating-lever, so as to be moved to release said drawer, and a locking device for said operating-lever which prevents it from being moved so as to unlock said money-drawer until the register is set to record a sale, said latter locking device controlled and operated by the reciprocating bars carrying the characters to be recorded.
11. A sales-recorder comprising a paper-holding device, a supporting device carrying a series of characters by which the registrations are made, an operating-arm, and a connecting device between said operating-arm and said paper-holding device adapted to move said paper forward step by step so as to leave a space between the successive registrations, said connecting device so constructed that said paper-holder is moved an increased amount at regular intervals so as to leave an enlarged space between the successive registrations.
12. A sales-recorder comprising a paper-holding device, a supporting device carrying a series of characters by which the registrations are made, an operating-arm, and a connecting device between said operating-arm and said paper-holding device adapted to move said paper forward step by step so as to leave a space between the successive registrations, said connecting device so constructed that said paper-holder is moved an increasing amount at regular intervals so as to leave an enlarged space between the successive registrations, and a perforating device associated with said paper-holder and adapted to perforate the paper between the registrations separated by said enlarged space.
